CHILD'S VEHICLE

Emanuel Pressner, South Orange, N.J., assignor to Banner Plastics Corporation, Paterson, N.J., a corporation of New York

Filed Mar. 27, 1959, Ser. No. 55,216

Term of patent 7 years

(Cl. D34—15)

FIG. I

FIG. 3

FIG. 2

FIG. 1 is a perspective view of a child's vehicle showing my new design;

FIG. 2 is a front elevational view of the child's vehicle shown in FIG. 1; and

FIG. 3 is a rear elevational view of the child's vehicle shown in FIG. 1.

The characteristic features of my new design are shown by full lines in the drawings.

I claim:

The ornamental design for a child's vehicle, as shown and described.
